ANGLE CONNECTOR FOR ELECTRIC CABLE
SUPPORTING TROUGH SYSTEMSFrederick G. W. Ullberg, Jr., Philadelphia, Pa.,
assignor to T. J. Cope, Inc., Philadelphia, Pa.,
a corporation of Pennsylvania

Application November 15, 1951, Serial No. 256,463

6 Claims. (Cl. 248—68)

1

This invention relates to angle connectors for trough units of systems designed for the support of heavy electric cables or the like in telephone, telegraph or power stations.

The chief aim of my invention is to provide a simple and inexpensive connector for uniting the meeting or confronting ends of horizontally and vertically arranged straight-away trough units in systems of the kind referred to, with means capable of sustaining the cables in such manner as to preclude sharp bending thereof and fracture or other injury to the insulation in which the conductors of the cables are embedded.

Other objects and attendant advantages will appear from the following detailed description of the attached drawings, wherein:

Fig. 1 is a fragmentary perspective view showing an angle connector conveniently embodying my invention, in position between and uniting one end of a horizontally-arranged straight-away cable trough unit to the confronting end of a vertically-arranged cable trough unit.

Fig. 2 shows the organization of Fig. 1 in longitudinal section on a larger scale.

Fig. 3 is a cross section taken as indicated by the angled arrows III—III in Fig. 2.

Figs. 4, 5 and 6 are perspective views of component parts of the connector.

As herein illustrated, the horizontal and vertical straight-away trough units 10 and 11 are fashioned from reticulate material which may be of the expanded metal variety, and the tops of their upstanding longitudinally-extending flanges 12 and 13 are finished off by lap-folded strips 14 and 15 of sheet metal.

The angle connector with which the present invention is more particularly concerned, is designated comprehensively by the numeral 16 in Fig. 1, component parts thereof being separately illustrated in Figs. 4, 5 and 6, and respectively designated comprehensively by the numerals 17, 18 and 19.

Component 17 has a transverse web 20 of reticulate material like that of the trough units 10 and 11, the ends of said web being marginally lapped over the cross portions of U-shaped straps 21 and welded or otherwise permanently secured thereto. As shown, the cross portions of the straps 21 are provided along opposite edges with spaced apertures 23 and 24, and their outstanding end portions with apertures 25, 26 in the transverse planes respectively of the first mentioned apertures.

Component 18 has side plates 27 of plain sheet material with bight edges 27a curved to coincide

2

with the curvature of the transverse web 20 of component 17, said plates being spaced to correspond with the spacing of the side flanges 12, 13 of the trough units 10 and 11. As shown, the side plates 27 are joined at the corners by a cross-wise bridging bar 29 of angular cross section said bar being welded or otherwise made fast and its horizontal flange is provided with longitudinally-extending rows of spaced apertures 30 for a purpose presently explained. Also as shown, the distal ends of the arms of side plates 27 of component 18 are pierced as at 31 and 32.

Component 19 (of which two are required) is in the form of a U-shaped strap like the end straps of component 17, and provided with correspondingly-spaced apertures 33, 34 in its cross portion and 35, 36 in its outstanding end portions.

To install the connector, the component 17 is applied from beneath and the ends of its transverse web 20 are brought into abutment with the corresponding ends of the trough sections 10 and 11 which latter are incidentally underlapped marginally by the strap 21, and the flanges 12, 13 are outwardly lapped by the end portions of said straps. Clamp straps 19 are thereupon applied from the sides opposite the straps 21 to correspondingly overlap the marginal portions of the trough unit ends and of the transverse web of the connector, whereupon securing bolts or rivets 37 are passed through the then registering apertures in the straps and through interstices of the interposed margins of the trough and of the web, as will be readily understood from Figs. 1-3.

To prevent sharp bending of the cables C, shown by broken lines in Figs. 2 and 3, at the regions of transition from the horizontal to the vertical, I have provided hangers in the form of hooks 38 whereof the shanks are selectively engageable upwardly through the apertures 30 in the cross bar 29 extending between the side plates 27 of component 18 of connector 16. By means of stop nuts 39 threadedly engaged upon the protruding upper ends of the shanks of the hooks 38, it is possible to adjust the latter up and down individually as may be required. Slings or grips 40 (see Fig. 2) applied to the vertical runs of the cables C below the bends of the latter, are connected to the hooks 38 through the medium of suitable links designated 41. It is to be particularly noted that the apertures 30 in the cross bar 29 are so located as to prevent the portions of the cables C within the confines of the trough unit 11 from contacting with the transverse web 20 or the side plates 27 of the

connector. Accordingly, in this way, injury to the cables, by sharp bending or abrasion, is effectively avoided.

I claim:

1. An angle connector for interposition between confronting ends of horizontally-arranged straightaway trough units having side flanges, said connector comprising a rounded transverse metallic web component; and a separable component having parallel side members of angular configuration fashioned from solid stiff sheet metal whereof the bights are curved to coincide with the rounding of the web component and spaced to correspond to the spacing of the side flanges of the trough units, and a rigidly united cross bar connecting the angle corners of the side members.

2. An angle connector for interposition between confronting ends of horizontally and vertically-arranged straightaway trough units, said connector having a rounded transverse web portion, parallel side members of angular configuration fashioned from solid stiff sheet metal whereof the bights are curved to coincide with the rounding of the web portion and spaced to correspond with the spacing of the side flanges of the trough units, a rigidly united cross bar connecting the angle corners of the side members; and cable hangers adjustably suspended from the cross bar.

3. An angle connector for interposition between confronting ends of horizontally and vertically-arranged straightaway trough units, said connector having a rounded transverse web portion, parallel side members of angular configuration fashioned from solid stiff sheet metal whereof the bights are curved to coincide with the rounding of the web portion and spaced to correspond with the spacing of the side flanges of the trough units, a rigidly united cross bar connecting the angle corners of the side members, and hanger hooks for suspension of individual cables, the shanks of the hooks being selectively engageable upwardly through spaced apertures in the cross bar and provided at their upper protruding ends with stop nuts for vertical adjustment of the hooks.

4. An angle connector for interposition between confronting ends of horizontally and vertically-arranged straightaway trough units fashioned from reticulate material, said connector comprising a component with a rounded transversely web of reticulate material and underslung U shaped straps with cross portions marginally overlapped by and attached to the ends of the transverse web; a component with parallel side members of angular configuration fashioned from stiff sheet metal and rigidly united at corners by a cross bar, the bights of said plates being curved to coincide with the rounding of the web of the first component, and the ends of the arms of said plates coinciding with the ends of said web so as to be overlapped to a corresponding extent by the upstanding ends of the straps when the components are placed with the ends of the cross web and the ends of the legs abutting the corresponding ends of the bottoms and the side flanges of the trough units; and smaller U shaped clamp straps corresponding to the straps of the first component and placed over the abutted edge margins of the transverse web of said first component for passage of securing means through the mutually overlapping portions of the trough sections and the connector.

5. An angle connector according to claim 4, further including cable hangers adjustably suspended from the cross bar joining the side plates of the connector.

6. An angle connector according to claim 4, further including hanger hooks for suspension of individual cables, the shanks of said hooks being selectively engageable upwardly through spaced apertures in the cross bar and provided at their upper protruding ends with stop nuts for the purposes of vertical adjustment of the hooks.

FREDERICK G. W. ULLBERG, JR.
